UNITED STATES PATENT OFFICE

ADOLPH KASSLER, OF NEW YORK, N. Y., ASSIGNOR TO AMERICAN CAR AND FOUNDRY COMPANY, OF NEW YORK, N. Y., A CORPORATION OF NEW JERSEY

HOPPER CAR

Application filed May 8, 1928. Serial No. 276,078.

This invention relates to railway cars and more particularly to dumping cars of the hopper type and it is an object of this invention to provide an improved construction of car of the type specified in which the bearings for the door operating mechanism will be positively positioned with respect to the draft sills and bolster and in which it will not be possible for the bearing to be shifted or disaligned.

It is also an object of this invention to provide an improved arrangement of bolster and draft sills in which the bolster is received in recesses in the draft sills.

15 In the drawings:

Figure 1 is a partial central, longitudinal, vertical section of a hopper car constructed in accordance with this invention;

Fig. 2 is a partial vertical transverse section taken on the line 2—2 of Fig. 1; and

Fig. 3 is a partial horizontal section taken on the line 3—3 of Fig. 1, the door operating mechanism being omitted.

In the drawings the car body is shown carried by a truck of the "bolsterless" type comprising wheels 1 fastened on axles 2 journaled in journal boxes 4 mounted in side frames 6. The side frames 6 are connected by transoms 8 and at their centers support truck bearings 10 upon springs 12 and 14. As the truck forms no part of this invention, it will not be described in detail, being shown only to make clear the manner of supporting the body and the relation of the body to its support. The upper surfaces of the bearings 10 are substantially spherical and carry body bearings 16 having similarly shaped engaging surfaces and which support the body bolsters 18, the bearings 10 and 16 being held in engagement by king pins 20. This arrangement provides a support for the car body at each of the corners thereof and the spherical surfaces of bearings 10 and 16 permit a swiveling of each side frame with respect to the car body sufficient to enable the trucks to travel the usual curves found in railways.

The body is shown as comprising a single hopper formed of side sheets 22, side slope sheets 24 and end slope sheets 26 and closed at the bottom by a plurality of longitudinally

extending doors 28 hinged at their outer longitudinal edges and operated by mechanism attached to the meeting edges of the doors and extending beneath the end slope sheets 26 of the hopper. Short side sills 30 and intermediate side sills 31 comprising spaced channels attached to the bolsters 18 extend from the end sills and bolsters respectively and are connected with the side sheets 22 and side slope sheets 24 by means of diaphragms 32 and straps 34 while to the end slope sheets 26 are connected angles 36. Braces 38 have their upper ends connected to angles 36 by gussets 40 and their lower ends connected by angles 42 to platform plates 44 which plates form parts of the car body bolsters 18. Plates 44 overlie the side sills 30 and 31, end sills 46 and draft sills 48 and are secured thereto by suitable rivet connections. To the upper edges of the end slope sheets are connected end supporting angles 50 which have their lower ends connected by angles 52 to the cover plate 44 and end sills 46.

The bolsters 18 are of unique construction and include a plurality of pressed channel-shape diaphragms 54 placed with their webs vertical and spaced apart and their flanges projecting outwardly. The diaphragms extend continuously from side sill to side sill with their top flanges horizontal and the diaphragm webs have their greatest depth adjacent the channel members 30, to which channel members the diaphragm webs and flanges are shaped to conform. Over the bearings 16 the diaphragm webs are of a uniform depth but less than their depth at the channels 30 after which the depth of the diaphragm webs gradually decreases and reaches its minimum at the axis of the draft sills. The bottom flanges of the diaphragms are connected by bottom cover plates 58 which extend continuously from end to end of the diaphragms and are attached to the bottom flanges of the channel side sills 30. Secured upon and to the upper flanges of the diaphragms are the platform plates 44 which form in effect intermediate bolster cover plates. Also forming parts of the bolsters are pressed reinforcing members 60 of inverted trough-shape with laterally project-

ing flanges at the center and gradually merging into plate portions 61 at the ends. The members 60 extend from end to end of the bolsters and are of such width that the rivets which secure the top flanges of the diaphragms 54 to the platform plates 44 also secure the members 60 to the intermediate cover plates by engaging in rivet openings in the plate portions 61 and in the flanges of the trough-shape portions of members 60.

10 Where the diaphragms 54 cross the sills 48, the sills are provided with flanged arms or brackets 68 which project outwardly from the sills beneath the flanges of the diaphragms 54 and are secured thereto by some of the rivets 55 which connect the bottom cover plate 58 to the diaphragms 54. The brackets 68 and the portions of the sills 48 beneath the bottom cover plate 58 together with the tie plates 69 and members 85 contribute to the strength and rigidity of the bolster structure at the center and are to be regarded as parts of the bolster structure. Thus there is produced a bolster of great depth at the middle 25 in which one of its essential elements 44 is fixedly secured to the end sill and for a considerable distance to the side sills of the car.

15 The draft sills 48 are substantially channel-shape with vertical webs and outwardly projecting flanges, the webs being of less depth at the diaphragms 54 to provide recesses which receive said diaphragms 54 and the bottom cover plates 58. The draft sills are formed as part of integral castings each of 20 which also includes a striking plate 62 which connects the outer ends of the draft sills. The draft sills are formed with front and rear stops 64 and 66, respectively, for the draft gear and with the integral flanged arms or 25 brackets 68 and a laterally extending perforated plate 70 which joins the inner ends of the draft sills 48 and is inclined at the slope of the end slope sheet 26 against which it bears and to which it is secured by the rivets 30 72. The plate 70 is of greater width than the distance between the draft sills 48 and the portions of said plate projecting beyond the sills 48 are braced by ribs 74 while the upper edge of the plate is provided with perforated 35 lugs or ears 76 in which is mounted the operating shaft 78 for the locking dog 80 of the door operating mechanism. The draft sills 48 are also joined by cross ties 82 and 84 formed integral with the draft sills 48, the 40 cross tie 82 having a horizontal portion to which the cover plate 44 is secured. Formed integral with the draft sills 48 adjacent the plate 70 are bearings 86 which project from the draft sills 48 and in which is mounted the 45 shaft 88 of a door operating mechanism 90 such as is shown in Patent No. 1,649,433, Wil- 50 loughby, November 15, 1927, and as the door operating mechanism forms no part of this invention it is not described in detail here.

55 It is to be understood that the drawings

herein are for illustrative purposes only and that various changes in the form and proportions of the device may be made within the scope of the appended claims without departing from the spirit of the invention.

70

What is claimed is:

1. In a hopper car, an integral draft sill casting comprising spaced channel shape sills recessed to receive bolster diaphragms, spaced outwardly projecting arms for attaching to said bolster diaphragms, a plate for engaging the end hopper sheet joining the inner ends of said sills and bearings for the hopper door operating mechanism on the sills adjacent said plate.

75

2. In a hopper car, an integral draft sill casting comprising spaced sills recessed to receive part of a bolster, outwardly projecting arms at said recesses for attaching to the bolster part, a plate for engaging the end hopper sheet joining the inner ends of said sills and lugs on said plate to support a shaft of the door operating mechanism.

80

3. In a hopper car, an integral draft sill casting comprising spaced sills recessed to receive part of a bolster, outwardly projecting arms at said recesses for attaching to the bolster part, a plate for engaging the end hopper sheet joining the inner ends of said sills, lugs on said plate to support a shaft of the hopper door operating mechanism and bearings on said sills for a second shaft of the door operating mechanism.

85

4. In a hopper car, an integral draft sill casting comprising spaced sills recessed to receive bolster diaphragms, outwardly projecting arms at said recesses for attaching to the bolster diaphragms, an inclined plate for engaging the end hopper sheet joining the inner ends of said sills, bearings for shafts of the door operating mechanism on said sills and plate and ties joining said sills at said recesses.

90

5. In a car, an integral draft sill casting comprising spaced sills recessed to receive a bolster part, a built up bolster resting in said recesses and a platform cover plate secured to said draft sills and extending between sections of said bolster.

95

6. In a car, an integral draft sill casting comprising spaced sills recessed to receive a bolster, outwardly projecting arms at said recesses and plates connecting the ends of said sills, a built up bolster aligned with said recesses and attached to said arms and a cover plate secured to said draft sills extending throughout the greater part of the length of said bolster between sections thereof.

100

7. In a car having side and end sills, draft sills extending from said end sill and provided with a bolster recess, arms projecting from said draft sills at said recesses, a sectional bolster extending through said recess and extending continuously from side sill to side sill, and a cover plate secured to said end and draft sills and extending from side sill

105

to side sill between sections of said bolster, said cover plate being secured to said bolster sections and said arms being attached to said bolster.

5 8. In a car having side and end sills, draft sills extending from said end sill and recessed to receive a bolster, arms projecting from said sills at said recesses, a sectional bolster extending from side sill to side sill through said recesses and attached to said arms and a cover plate attached to said end, draft and side sills and bolster and extending between sections of said bolster.

10 9. In a car having draft sills recessed to receive a bolster, a sectional bolster comprising flanged diaphragms in said recesses, a platform-cover-plate attached to said draft sills and diaphragms and an inverted trough-shape bolster member attached to said cover plate and diaphragms.

15 10. In a railway car, an end platform construction comprising cast draft sills recessed in their upper portion, bolster diaphragms resting in said recesses, a platform-bolster-plate secured to said sills and diaphragms, and an inverted trough-shaped bolster member overlying and being secured to said platform-bolster-plate.

20 11. In a railway car, a combined end platform and bolster comprising recessed draft sill portions, bolster diaphragms resting in the recesses, a platform-bolster-cover plate connecting the draft sills and said diaphragms and an inverted trough-shaped upper bolster member directly connected with said plate and said diaphragms.

25 12. In a hopper car, a combined end platform and bolster including draft sill portions and transversely extending bolster portions, side sills, an end sill and a platform plate forming a bolster cover plate intermediate said bolster portions.

30 13. In a car construction, side and end sills, a built up bolster including a platform plate forming the bolster-cover-plate and connecting said side and end sills.

35 14. In a car construction, side and end sills, a bolster comprising a plurality of sections, each section extending from side sill to side sill, and a platform plate joining said side and end sills and extending between said bolster sections to form a bolster cover plate.

40 15. In a car construction, side and end sills, a bolster having a raised central portion comprising a plurality of sections, each section extending from side sill to side sill, and a platform plate joining said side and end sills and extending in a horizontal plane between said bolster sections to form a bolster cover plate.

45 In witness whereof I have hereunto set my hand.

ADOLPH KASSLER.
